TYPEWRITING MACHINE

Lewis C. Myers, Freeport, N. Y., assignor to Royal
Typewriter Company, Inc., New York, N. Y., a
corporation of New York

Application March 24, 1933, Serial No. 662,581

8 Claims. (Cl. 197—114)

This invention relates to new and useful improvements in typewriters generally, although more particularly to a noise reducing stop for the manually operable line spacing lever.

Heretofore these manually operable line spacing levers have been spring returned against a fixed metal stop and the impact of the levers against the stop has always resulted in considerable noise.

Among the several objects of this invention are to provide a metal stop which is yieldable under impact by the line spacing lever when the latter is returned to its normal position thereby creating a noise reducing stop; to provide such a yieldable stop which will be certain in its function and durable in operation, and to provide a stop construction for the purpose set forth which is simple, cheap to manufacture, and capable of being readily applied to commercial machines without any material change thereto.

With these and other objects in view which will more fully appear, the nature of the invention will be more clearly understood by following the description, the appended claims, and the several views illustrated in the accompanying drawing.

In the drawing:—

Figure 1 is a top plan view of one end of the carriage showing the usual line spacing mechanism and also showing my improved stop means for the manually operable lever of the line spacing mechanism, the view showing the line spacing lever in its normal position.

Figure 2 is a somewhat similar view but showing the line spacing lever in its operative position, a portion of the carriage shelf being broken away to better disclose the stop lever.

Figure 3 is an end elevation of the carriage and line spacing mechanism, parts thereof being shown in section.

Figure 4 is an enlarged detail sectional view showing the mounting of the line spacing lever and the yieldable stop therefor.

Figure 5 is a perspective view of the stop lever, and

Figure 6 is a perspective view of the anchor arm.

Referring to the accompanying drawing, A designates the frame of a typewriting machine on which a carriage B is mounted in the usual manner for line spacing movements. This carriage includes an end wall 5 and journaled in this end wall is one end of a rotary platen C. Fixed to the end of the platen adjacent the end plate 5 is a ratchet wheel 6. Extending outwardly from the upper edge of the end plate 5 adjacent the

platen C, is a shelf 7 and pivoted on this shelf is the usual manually operable line spacing lever D which includes an operating arm 8 and an actuating arm 9, the latter being connected by a link 10 to an arm carrying a pawl 11 which cooperates with the ratchet wheel 6 in the usual manner to effect a line spacing movement to the platen C upon movement of the lever D. This manually operable lever D is in the nature of a bell crank and the arm 9 thereof projects in the general direction of the platen C. Depending from the lever D at its angle is a rigidly connected pivot pin 12 which is mounted for oscillations in an opening formed in the shelf 7.

A stop lever E which includes aligned arms 13 and 14, is pivoted intermediate said arms to the under face of the shelf 7 by a pivot pin 15 which is located between the fulcrum 12 and the end plate 5 of the carriage. The longitudinal axis of the stop lever E extends lengthwise of the end plate 5, and the free end of the arm 13 projects upwardly and terminates in an upwardly extending stop 16 adapted for cooperation with the actuating arm 9 of the manually operable lever D. The free end of the arm 14 of the stop lever E terminates in an outwardly extending anchor arm 17. An anchor arm 18 is provided with an angular recess 19 which fits a correspondingly shaped shoulder on the lower end of the pivot pin 12. This arm 18 is secured to the pivot pin 12 by a screw 20. The arm 18 is thus rigidly secured to the bell crank lever D and extends in a direction from the pivot pin 12 opposite the actuating arm 9. A coil spring 21 is connected at one end to the anchor arm 17 of the stop lever E and at its other end to the anchor arm 18 of the manually operable line spacing lever D.

From the foregoing, it will be observed that I have provided a yieldable metal stop for the lever D; that this stop is pivotally mounted on the shelf 7 on which the manually operable lever D is also pivoted, and that a single coil spring 21 connects the stop lever E with the line spacing lever D. When the lever D is in its normal position the forward arm 13 of the stop lever E is held in yieldable contact with the end wall 5 of the carriage by the spring 21 and the spring 21 also functions to yieldably retain the arm 9 of the lever D against the stop 16 of said stop lever. When the arm 8 of the lever D is moved toward the right to actuate the line spacing ratchet wheel 6, tension is applied to the spring 21 and this tension causes the lever D when released to return to its normal position. As soon as the line spacing movement has been effected, the lever D is

released and the spring 21 will return said lever to a position of engagement with the upstanding stop 16 of the stop lever E, the stop 16 of the lever E being slightly moved beyond its normal position in a direction towards the pivot of the lever D by the angled relation between the stop arm 16 and the contacting face of the arm 9 of the lever, thereby tensioning the spring 21 and constituting a yieldable stop for the lever and to also 5 greatly reduce the noise of impact.

10 After the above action has taken place the arm 13, under the tension of the spring 21, returns to its normal stopped position against the plate 5 as shown in full lines in Figure 2, the line 15 spacing lever also assuming its normal position as shown in Figure 1.

I claim:—

1. In a typewriting machine, the combination with a platen, of a line spacing mechanism therefor including a manually operable lever, a pivotally mounted stop directly engageable by said lever to limit the return movement of the latter, and a spring connected to the stop and connected to a part of the typewriting machine for yieldably resisting the lever impact against the stop. 20

2. In a typewriting machine, the combination with a platen, of a line spacing mechanism therefor including a manually operable lever, a pivotally mounted stop directly engageable by said lever to limit the return movement of the latter, and a single spring directly connecting the lever 30 and the stop for yieldably resisting the lever impact against the stop.

3. In a typewriting machine, the combination with a carriage including an end plate having an outwardly extending shelf, of a rotary platen having one end journaled in said end plate adjacent said shelf, a line spacing mechanism for the platen including a manually operable bell crank lever fulcrumed at its angle on said shelf, a two-armed lever fulcrumed on said shelf and terminating at one end with an upstanding stop for limiting the return movement of the manually operable lever, and a coil spring connected at one 40 end to the manually operable lever and at its other end to the end of the two-armed lever opposite the stop for yieldably resisting the lever impact against the stop.

4. In a typewriting machine, the combination with a carriage including an end plate having an outwardly extending shelf, of a rotary platen having one end journaled in said end plate adjacent said shelf, a line spacing mechanism for the platen including a manually operable bell crank lever fulcrumed at its angle on the upper face of said shelf, a two-armed lever fulcrumed on the lower face of said shelf and terminating at one end with an upstanding stop for limiting the return movement of the manually operable lever, and a coil spring connected at one end to the manually operable lever and at its other end to the end of the two-armed lever opposite the stop for yieldably resisting the lever impact against the stop. 50

5. In a typewriting machine, the combination with a carriage including an end plate having an outwardly extending shelf, of a rotary platen having one end journaled in said end plate adjacent said shelf, a line spacing mechanism for the platen including a manually operable bell crank lever fulcrumed at its angle on the upper face of said shelf, said lever including an actuating arm extending towards the platen, a two-armed lever

fulcrumed on the lower face of said shelf and terminating at one end with an upstanding stop for limiting the return movement of the manually operable lever, the fulcrum of the two-armed lever being located between the fulcrum of the manually operable lever and the end plate of the carriage, the longitudinal axis of the two-armed lever extending lengthwise of said end plate, the end of the two-armed lever opposite the stop extending outwardly beyond the fulcrum of said lever, and a coil spring connected at one end to the manually operable lever and at its other end to the outwardly extending end of the two-armed lever opposite the stop for yieldably resisting the lever impact against the stop, the stop end of the two-armed lever being normally in contact with the end plate of the carriage. 80 85 90

6. In a typewriting machine, the combination with a carriage including an end plate having an outwardly extending shelf, of a rotary platen having one end journaled in said end plate adjacent said shelf, a line spacing mechanism for the platen including a manually operable bell crank lever fulcrumed at its angle on the upper face of said shelf, said lever including an actuating arm extending towards the platen, a two-armed lever fulcrumed on the lower face of said shelf and terminating at one end with an upstanding stop for limiting the return movement of the manually operable lever, the fulcrum of the two-armed lever being located between the fulcrum of the manually operable lever and the end plate of the carriage, the longitudinal axis of the two-armed lever extending lengthwise of said end plate, the end of the two-armed lever opposite the stop extending outwardly beyond the fulcrum of said lever, an anchor arm fixed to the manually operable lever and projecting in a direction opposite the actuating arm thereof, and a coil spring connected at one end to the anchor arm of the manually operable lever and at its other end to the outwardly extending end of the two-armed lever opposite the stop for yieldably resisting the lever impact against the stop, the stop end of the two-armed lever being normally in contact with the end plate of the carriage. 100 105 110 115 120

7. In a typewriting machine, the combination with a platen, of a line spacing mechanism therefor including a manually operable lever, a stop lever fulcrumed at a point in spaced relation to the fulcrum of the manually operable lever and having a stop normally spaced from the fulcrum of said manually operable lever but engageable by said manually operable lever and movable towards the fulcrum thereof during return movement of the latter, and a spring connected to the stop lever for yieldably resisting the lever impact against the stop. 12 13

8. In a typewriting machine, the combination with a platen, of a line spacing mechanism therefor including a manually operable lever, a stop lever fulcrumed at a point in spaced relation to the fulcrum of the manually operable lever and having a stop normally spaced from the fulcrum of said manually operable lever but engageable by said manually operable lever and movable towards the fulcrum thereof during return movement of the latter, and a single spring connecting the manually operable lever and the stop lever for returning said manually operable lever and for yieldably resisting the impact thereof against the stop. 13 14
